UNITED STATES PATENT OFFICE.

WILLIAM J. FINN, OF SCRANTON, PENNSYLVANIA

COMBINED TRY-SQUARE AND SIDING-GAGE.

No. 686,885.

Specification of Letters Patent.

Patented May 26, 1902.

Application filed July 26, 1897. Serial No. 385,559.

To all whom it may concern:

Be it known that I, WILLIAM J. FINN, a citizen of the United States, residing at Scranton, in the county of Lackawanna and State of Pennsylvania, have invented certain new and useful Improvements in Combined Try-Squares and Siding-Gages, of which the following is a specification.

My invention relates to improvements in combined try-squares and siding gages, the same also being applicable for mitering purposes, and for marking off material in producing angles generally. Its object is to provide an instrument of the above suggested character for securing the results aforesaid in a simple, accurate, and effective manner.

My invention consists of certain instrumentalities substantially as hereinafter fully disclosed and pointed out by the claims.

In the accompanying drawing illustrating the preferred embodiment of my invention—Figure 1 is a side view thereof. Fig. 2 is an opposite side view of the same. Fig. 3 is an end elevation of the device as applied to the corner. Fig. 4 is a side view showing the instrument as adapted for mitering purposes and marking off material for cutting angles generally. Fig. 5 is a view in side elevation, with the parts as applied for actual use as a siding gage—more especially for marking siding for cutting. Fig. 6 is a like view with the device as applied more particularly for supporting the siding while nailing it, it having been previously marked and cut. Fig. 7 is a detail section showing the pinion for operating the rack. Fig. 8 is a cross-section through the same.

In carrying out my invention, the same is conformed generally after the fashion of a try-square 1 with both members thereof scribed with the usual graduations in inches and fractions thereof. One member, as for instance the handle 1^a, has in one edge a reduction or recess 2 which, in practice, receives the siding as shown preliminary to the marking thereof for cutting. Suitably or slidably connected to this same member, is an adjustable plate-member or gage 3 having a longitudinal slot 4 therein receiving a suitable nut-equipped fixing pivot-bolt 5, projecting from said handle-member and also supplemented by the action of a jam-nut *a*. The pivot-bolt 5 of the gage 3 is also provided with a pinion or ratchet 6 engaging a rack or serrated surface *c* provided along one edge of a

slot 4 in said gage or plate-member 3 for the requisite adjustment and retention in place of said gage for its intended purpose as presently disclosed. The upper end of said plate-member or gage has a beveled sharp-point 6 at its forward edge, effective, under suitable pressure, to enter and form a dent or mark in the siding or board previously secured in place for guidance in superposing the following siding or board, as will be readily understood from Fig. 6. In thus positioning the device, it is applied with the member 1^a, which may be termed the siding hook, so as to allow the bottom of the recess 2 to take under the bottom edge of a previously secured board or siding and the upper forward inclined edge 7 of said member or hook to rest against the outer surface of a second board or siding temporarily retained in place. The plate-member or gage 3, which has two spaced-apart notches 8, 9, in its top edge, is now moved upon its pivot-bolt 5 until its said top edge is so adjusted as to allow the inner edge of the recess 2, appearing thereabove as seen in Fig. 6, to occupy a position relatively intermediate of said notches. The upper forward end 5^a of said gage or plate-member 3 is now pressed inward sufficiently to cause its sharp point 6 to produce the required mark or indentation for guidance for suitably placing or securing the following board or siding.

As above noted, Fig. 6 suggests the application of the device, as when it may be required to mark a board or siding for cutting, the latter being let into the recess 2 of the siding hook-member 1^a and which hook-member is equipped upon one side with a plate 10 having preferably a series of points or saw-teeth projecting sufficiently beyond the inner or longitudinal edge of the recess 2 to allow said points or surface, by suitably manipulating the device, to effect the required marking of said board or siding, as will be readily appreciated.

For using the device for mitering purposes or marking out material upon angular lines it is only necessary to refer to Fig. 4 from which it is thought that the same will be readily apparent. Also it is noted that the blade-member of the try-square, especially as seen in Figs. 5, 6, is equipped along one edge with a continuous series of notches 11 each representing a sixteenth of an inch being suitably graduated to that end, and which may be brought into service by engag-

ing the same, for instance, with the point of a pencil for suitably effecting the requisite movement of the part or member to be manipulated, as in producing a straight line or lines with said pencil point upon, and parallel with the edge of a board, the try-square being moved along the latter by the pencil as it is thought will be readily appreciated.

I claim—

- 10 1. A combined try square and siding gage, the handle member of which has the usual straight inner edge and is provided with fixed shoulders or enlargements, the outer edges of which are disposed at an angle to the said straight edge of the said member.
- 15 2. A combined try square and siding gage, the handle member of which has the usual straight inner edge and is provided with fixed shoulders or enlargements, the outer edges of which are disposed at an angle to the said straight edge of the said member, and a gage slidably and pivotally connected with one member of the square.
- 20 3. A combined try square and siding gage, the handle member of which has the usual straight inner edge and is provided with fixed shoulders or enlargements, the outer edges of which are disposed at an angle to the said straight edge of the said member, and a gage slidably and pivotally connected with one member of the square, the gage provided with a sharp point at one end, which extends in the direction of the shoulders or enlargements.
- 25 35 4. A device as described, comprising a try-square, one member of which is adapted for application to a siding or board and a gage or plate member pivoted to, and adjustable

upon said try-square member and having at one end spaced-apart notches and at the forward edge of the same end a marking or indenting point.

5. A device as described, comprising a try-square, one member of which is adapted for application to a siding or board and a gage or plate member provided with a longitudinal slot, a longitudinal edge of which is provided with a series of teeth, and provided at one end, at its forward edge, with a marking point, and a pivot-bolt for said gage carrying a ratchet engaging said teeth of said gage.

6. A device substantially as described, comprising a square and a gage pivotally connected at one end to the square, said gage having a longitudinal slot with one toothed edge, the pivoting bolt of the gage having a pinion for adjusting the gage lengthwise as it is turned.

7. A device, substantially as described, comprising a square and a gage pivotally connected at one end to the square, said gage having a longitudinal slot with one toothed edge and pivoting bolt for the gage, having a pinion thereon for adjusting the gage lengthwise as the pinion is turned, a knurled head on one end of the bolt to facilitate the turning of the latter, the opposite end of the bolt screw-threaded and a nut thereon for locking the bolt against turning.

In testimony whereof I affix my signature, in presence of two witnesses.

WILLIAM J. FINN.
